UNITED STATES PATENT OFFICE.

WALTHER WOLFF, OF KARLSHORST, GERMANY, ASSIGNOR TO GENERAL ELECTRIC COMPANY, A CORPORATION OF NEW YORK.

VACUUM-TUBE CONNECTION.

Application filed January 31, 1924, Serial No. 689,717, and in Germany February 9, 1923.

My present invention relates to vacuum tube connections, and more particularly to connections for supplying heating current to the cathodes of vacuum tubes of the thermionic type.

The object of my invention is to provide a connection whereby it will be possible to automatically close the heating circuit for thermionic cathodes of amplifier tubes used in telephone operation before a conversation is started over a telephone line, then to again open the circuit when the conversation is finished.

It has previously been proposed to accomplish this result by means of automatic selective devices such as those employed in automatic telephone service. Such apparatus requires numerous switching devices which may be employed when a large number of connections are to be made, but are unduly expensive when only a small number of connections is required.

In carrying my invention into effect I provide for the closing of the heating circuit when a call is made over the line and for the opening of the heating circuit at the close of the conversation by sending over the line a second impulse similar to the calling impulse.

The novel features which I believe to be characteristic of my invention are set forth with particularity in the appended claims. My invention itself, however, will best be understood by reference to the following description taken in connection with the accompanying drawing in which Figs. 1 and 2 show respectively two different circuit organizations whereby my invention may be carried into effect.

In Fig. 1, I have indicated a telephone line F^1 , which terminates at the points a and b . The connection of this line to the thermionic amplifiers 1 and 2 of any usual type, which are employed for amplifying the conversation sent over the line is omitted as such connection forms no part of my invention. Between the points a and b , there is connected the winding of a relay 3, which is adapted to close a contact at 4. The heating circuit of the cathodes 5 of the amplifiers 1 and 2 comprises the usual battery 6 and the regulating resistance 7. This circuit is brought to the points X and Y . When a call is sent over the line F^1 , relay 3 operates to close contact 4. This closes the

heating circuit from point Y through contact 4, connection 8, contact 9, connection 10, the windings of relays 11 and 12, to point X . The holding relay 11 then closes contact at 13, so that after the calling current has stopped the heating circuit remains closed between X and Y , through the windings of relays 11 and 12 and contact 13. Hence the amplifiers 1 and 2 will remain in their excited condition and conversation over the line can be effected.

In order to prevent the heating circuit from being opened and closed during the continuance of conversation, the retarding relay 14 is provided which permits the opening of the heating circuit only after the end of the conversation and after a period of 5 to 10 seconds has elapsed after the original closing of the circuit.

When the relay 12 is energized by the closing of the heating circuit, contact is made at 15. This closes a circuit from the positive pole of battery 16 through contact 15 to the winding of relay 14, contact 17, through the connection 18 back to the negative pole of battery 16. After a period of 10 or 15 seconds, relay 14 operates, closing contact 19. This closes a circuit from the positive pole of the battery 16 through contact 15, relay 14, contact 19, through the winding of relay 20, and back through the connection 18 to the negative pole of battery 16. When the relay 20 is energized it breaks contact at 9 and 17, and makes new contacts at 21 and 22. By the breaking of contact 17, the circuit for the retarding relay 14 is interrupted so that the contact is broken at 19. Relay 20, however, remains excited by reason of the circuit which is established from the positive pole of battery 16 through contacts 15, 21, through the winding of relay 20, and the connection 18 back to the negative pole of battery 16.

By the operation of relay 20, the system is prepared for the opening of the heating circuit. For this purpose a special call is sent over the line F^1 after the termination of the conversation. By this call the relay 3 is again excited, making contact at 4. By this contact the heating circuit is closed from Y through contact 4, connection 8, contact 22, connection 23, through the winding of relay 12, to the point X . It will be observed that by this operation the circuits are so changed that relay 11 is no longer excited,

- consequently the contact at 13 is opened. As soon as the stop call terminates the relay 3 releases its armature opening contacts at 4 and 22, thus opening the heating circuit. 60
- Relay 12 is then deenergized and contact is broken at 15 thus deenergizing the winding of relay 20. Contacts 9 and 17 are thereupon made again and the relay system is ready to operate to establish a new connection.
- 10 In the connection shown in Fig. 2 the retarding relay 14 is omitted. Calling relay 3 in this case has three contacts 24, 25 and 26. When a call is sent over the line the relay 3 is energized and contacts 24 and 26 are made 65
- 15 and contact 25 is broken. The heating circuit is then closed from Y through contacts 24 and 27, through the winding of relay 28 to X. Relay 28 now makes contacts at 29, 30; so that after completion of the calling 70
- 20 signal the heating circuit remains closed from Y through contact 29, through the winding of relay 28 to point X. At the same time contact is established at 25 and a circuit is closed from the positive pole of 75
- 25 battery 16 through contacts 30 and 25, and the winding of reversing relay 31 back to the negative pole of the battery 16. The relay 31 being energized, opens contact 27, and closes contacts at 32 and 33, and thereby 80
- 30 puts the system in condition for the opening of the heating circuit.
- To effect the opening of the heating circuit after conversation is terminated, the closing call is sent over the line F¹. Calling relay 3 is thus excited and contacts again made at 85
- 35 24 and 26. Current then flows through a circuit from point Y, contact 24, contact 32, and connection 33 to point X. By this change in the connections the relay 28 is de- 90
- 40 energized and hence contacts 29 and 30 are broken. Relay 31, however, remains energized by reason of the circuit established from the positive pole of battery 16 through contact 26, connection 34, contact 33, through 95
- 45 the winding of relay 31, back to the negative pole of battery 16. Hence the contacts 32 and 33 are maintained until the end of the final call. After the final call has terminated, contacts 24 and 26 are broken and the 100
- 50 heating circuit is opened. The circuit of relay 31 is also opened by the opening of contact 26 and the relay system is again ready to operate to establish a new connection.
- 55 What I claim as new and desire to secure by Letters Patent of the United States, is:—
1. The combination in a telephone system employing a thermionic amplifier, of means responsive to a calling current for closing and opening a heating circuit for the amplifier cathode. 60
2. The combination in a telephone system employing a thermionic amplifier, of means responsive to a calling current for closing and opening a heating circuit for the amplifier cathode, and means for maintaining the heating circuit closed during the continuance of a conversation. 65
3. The combination in a telephone system employing a thermionic amplifier, of means responsive to a calling current for closing a heating circuit for the amplifier cathode, means for maintaining the heating circuit closed during the continuance of a conversation, and means responsive to a calling current for opening the heating circuit after the close of a conversation. 70
4. The combination in a telephone system employing a thermionic amplifier, of a relay responsive to a calling current for closing a heating circuit for the amplifier cathode, and means actuated by said relay for maintaining the heating circuit closed when said calling current has ceased to flow and during the continuance of a conversation. 75
5. The combination in a telephone system employing a thermionic amplifier, of a relay responsive to a calling current for closing a heating circuit for the amplifier cathode, and means comprising a second relay which is actuated by the operation of the first relay for maintaining the heating circuit closed when said calling current has ceased to flow and during the continuance of a conversation. 80
6. The combination in a telephone system employing a thermionic amplifier, of a relay responsive to a calling current for closing a heating circuit for the amplifier cathode, means comprising a second relay which is actuated by the operation of the first relay for maintaining the heating circuit closed during the continuance of a conversation, and a third relay which is actuated as a result of the actuation of the first relay and the actuation of which changes the circuit connections to permit the opening of the heating circuit by a second actuation of the first relay. 100
- 105
- In witness whereof, I have hereunto set my hand this 15th day of January, 1924.
- WALThER WOLFF. 110
